(57) CLAIM

The ornamental design for pants, as shown and described.

DESCRIPTION

FIG. 1 is a front view of pants according to a first embodiment
of the design;

FIG. 2 is a back view thereof;

FIG. 3 is a right side view thereof;

FIG. 4 is a left side view thereof;

FIG. 5 is a front view thereof shown in use;

FIG. 6 is a front view of pants according to a second embodiment
of the design;

FIG. 7 is a back view thereof;

FIG. 8 is a right side view thereof;

FIG. 9 is a left side view thereof;

FIG. 10 is a front view thereof shown in use;

FIG. 11 is a front view of pants according to a third embodiment
of the design;

FIG. 12 is a back view thereof;

FIG. 13 is a right side view thereof;

FIG. 14 is a left side view thereof;

FIG. 15 is a front view thereof shown in use;

FIG. 16 is a front view of pants according to a fourth embodiment
of the design;

FIG. 17 is a back view thereof;

FIG. 18 is a right side view thereof;

FIG. 19 is a left side view thereof; and,

FIG. 20 is a front view thereof shown in use.

The symbol depicted in FIGS. 2-4 and 7-9 forming part of the claimed design is a registered trademark of Lululemon Athletica Canada Inc.
